UNITED STATES PATENT OFFICE

NIELS HANSEN JENSEN, OF PORTLAND, OREGON

COMBINATION BENCH AND WRITING DESK

Application filed November 5, 1928. Serial No. 317,251.

The device consists primarily of framed elements joined together and consisting primarily of a back frame to which are secured end frames and having disposed therebetween and hingedly secured thereto two sections, one of which forms the back of the device when raised, into which a plurality of illustrated and descriptive units are removably disposed, and one end of which carries a mirror, the remaining section carrying a desk and drawer unit with individual covered sections disposed at oppositely disposed ends and having a central drawer section.

15 The primary object of the device is to provide a bench, or settee, and usable as such, as a high grade piece of furniture and which may be easily and quickly transformed into a writing desk.

20 One of the objects of the device consists in a simplified construction and one that may be transformed from a settee, to a working writing desk, with the writing materials exposed to view upon the transforming of the same from a settee to a writing desk.

A further object of my invention resides in a writing desk, when transformed as such, with a desk lamp disposed within the device 25 that may be brought into use, upon the transforming of the same into a writing desk.

A further object of my invention resides in a simplified construction in which the seat portion of the same, when used as a settee, may be raised to form a back for the writing desk with educational data removably disposed within the back that will be exposed to view when raised.

30 A further object of my invention resides in a construction that maintains the frame in a relatively rigid condition whether in use as a settee or as a writing desk.

A further object of my invention resides in a writing desk structure having compartments disposed in oppositely disposed ends that are provided with a hinged lidded closure that is self-supporting when closed and providing a spaced relationship between the working surface of the writing desk with 45 that of the settee lid so that the materials

to be worked upon in the writing desk may be exposed and left in a working condition when the device is transformed from a settee to a writing desk.

With these and incidental objects in view, 55 the invention consists in certain novel features of construction and combination of parts, the essential elements of which are set forth in the appended claims, and a preferred form of embodiment of which is 60 hereinafter shown with reference to the drawings which accompany and form a part of this specification.

In the drawings:

Fig. 1 is a perspective, front view of the 65 assembled device in position to be used as a settee.

Fig. 2 is a perspective, front view of the 70 assembled device, shown in position for use as a writing desk.

Fig. 3 is a sectional, front view of the 75 assembled device, shown in position for use as a writing desk.

Fig. 4 is a vertical, sectional, end view of the assembled device, as a settee.

Fig. 5 is a sectional, end view of the 80 assembled device, shown in position for use as a writing desk.

Fig. 6 is a fragmentary, sectional, front view of one corner of the device, made to 85 illustrate the depressible lamp disposed within the frame structure illustrating the lamp in repressed position.

Fig. 7 is a fragmentary, sectional, front view of the frame illustrating the lamp in 90 raised position.

Fig. 8 is a fragmentary, sectional, end view of the assembled device made to illustrate the construction of the settee lid.

Like reference characters refer to like 95 parts throughout the several views.

I preferably form my device of a back frame member 1, having end frame members 2 and 3 being joined to the back frame by any suitable fastening means. Rails 4 and 5 are disposed across either of the said sections and the same being secured to the primary back frame 1, by suitable gusset plates 7 and 8. The gusset plates being so arranged as to stiffen the side frame members. Guide- 100

ways 9 and 10 are disposed in the rails 4 and 5 with an upturned ledge disposed parallelly of the guide, as illustrated at 11 and 12 in Fig. 3. Projections 13 and 14 downwardly extend from the lower side of the writing desk 15, and are adapted to engage within the guideways 9 and 10 of the rails to stiffen the frame when the device is to be used as a settee. A writing pad 16 is disposed centrally of the upper surface of the writing desk 15 with an opening disposed at either end of the writing table surface. Lidded closures 17 and 18 are hingedly secured to the table members 15 and are hinged to the rail 19, as illustrated in Fig. 3. The inner edge 20 of the closure being adapted to engage, when closed, with the underside of the rail 19, thus requiring no additional support for the closure other than that of the hinge 21 that secures the closure to the rail 19. A ledge is formed about either end and the back side of the writing desk, as shown at 19 and 23, that upwardly extend from the writing surface, and a lip 24 is disposed about the lower underside of the lidded closure that forms the seat of the settee so that a space is maintained between the upper surface of the writing table and the lower surface of the seat member. The purpose and object of which is to provide a space for writing materials that may be left upon the writing table when the same is transformed from a writing desk to that of a settee. The writing table is hingedly supported relative to that of the frame by hinging links 25 and 26, disclosed in Fig. 5, and the same are so arranged that when the writing table is raised into writing position, the links pass the vertical center of the supporting pins 27 and 28 to maintain the writing table in a state of equilibrium. When the writing table has been lowered into the position of inactivity, the under surface of the table as illustrated at 13 and 14 will engage within the guideways of the rails 5 and 6. This engagement also maintains the assembled device in a stabilized condition. The links serving the purpose of supporting the table when in use as a writing table and for acting as guideways and supporting links in the raising and lowering of the table into and out of the position from that of a writing table to that of a settee. The seat section is hinged relative to the writing table by any suitable hinge 29, illustrated in Fig. 5, and the link 30 maintains the lid hingedly fixed to that of the writing table. When the seat section has been raised in the elevated position the ledge 31 engages the upper side 32 of the back frame and the links maintain the same in a raised position. A series of slots 33 are disposed within the front rail 34 of the seat and the same are within registerable alignment within the slots disposed within the back rail 35 of the seat into which units 36 may be

slidably disposed within the slots to facilitate the movement of the units 36 longitudinally of the slots. The spaced distance between the bottoms of the slots should be greater than that of the units 36 being disposed therein, so that by the raising of the unit 36 when the lid is in position, as illustrated in Fig. 8 to the full bottom of the slot, the unit 36 may then be removed from the engaging slots and other and different unit be placed therein. A suitable upholstery covering 37 being placed on the top of the seat with the covering 38 disposed thereupon. A mirror 39 or any other suitable device may be placed within the inside of the lid, as illustrated in Fig. 2. A recess 40 is disposed within one corner of the frame into which a block 41 is slidably disposed. A lamp bearing arm 42 is hingedly secured to the block, as illustrated in Fig. 6 and an electric conductor 43 connects the switch block 44 with that of the lamp arm. A protecting cover 45 is hingedly disposed at the upper end of the arm 42 and is secured thereto, by any suitable hinging connection 46. The closure 45 acting as a cover for the recess 40 and as a protection for the lamp 47 terminating the arm. A supporting ring 48 is disposed about the arm and is adapted for being positioned along the arm at any desired location. As the lamp arm is withdrawn from the recess 40, the supporting ring 48 may be made to engage and rest upon the upper wall 49 of the frame, as illustrated in Fig. 7, thereby maintaining the lamp in the desired elevation and position.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, comprising a back frame and end frame members having grooved rails horizontally positioned on the inner side of the end frame members, a seat member hingedly disposed within the frame, said seat member having front and rear rails having grooves disposed within their inner surface for placing educational units within them and a writing desk hingedly connected to and a part of the seat member recesses disposed in the upper and oppositely disposed ends of the desk, hinged closures for each of the recesses, with a writing surface disposed between the recesses, means for maintaining the desk element relatively fixed when in lowered normal position to stiffen the frame of the device and means for raising the desk element and for locking the same relative to

the frame when raised to writing position and means for maintaining the upper writing surface of the desk element and the lower surface of the seat element in spaced relation when the device is being used as a settee.

2. In a device of the class described, the combination of a framed structure composed of back and end frames rigidly secured to each other, an upholstered seat comprising two sections hingedly secured to each other and to the back frame the upper section adapted for being used as a seat and as a back for a writing desk, the lower section adapted for use for stiffening the frame and as a writing desk and means for actuating the sections into and out of writing position relative to the frame.

3. In a device of the class described, the combination of a frame, a seat member comprising a seat section and a writing desk section each hinged relative to the other, the desk section being hingedly secured to the frame to form a device normally to be used as a settee and means for actuating the seat section into a back for a writing desk and for actuating the desk section into position for use as a writing desk and means for maintaining the oppositely disposed surfaces of the desk and the seat section in spaced relation when the device is being used as a settee.

4. In a device of the class described comprising a settee frame, a seat member having two sections disposed one above the other maintaining a close relationship with and hingedly secured to each other, the lower section having downwardly extending parallel projections disposed in spaced relation at its bottom in registerable alignment with bifurcated guideways secured to the end members, a writing pad being disposed centrally of the said section with lidded openings disposed on either side of said writing pad, a plurality of hinging links hingedly connected to said section at its side and back and to the settee at its end members and back permitting the free movement of the combined member from its position as a seat to its position as a writing desk back and writing desk, the upper section having a ledge running longitudinally of its back adapted to disengagedly engage the top of settee back, a plurality of grooves disposed within the section and units disposed within the grooves.

NIELS HANSEN JENSEN.
